UNITED STATES PATENT OFFICE.

DANIEL F. LEPELEY, OF CONNELLSVILLE, PENNSYLVANIA.

OVERTURNING CAGE.

Application filed October 22, 1921, Serial No. 509,651.

To all whom it may concern:

Be it known that I, DANIEL F. LEPELEY, a citizen of the United States, residing at Connellsville, in the county of Fayette and State of Pennsylvania, have invented a new and useful Overturning Cage, of which the following is a specification.

This invention relates to overturning cages such as used in mine shafts.

Heretofore difficulty has been experienced in operating an overturning cage or platform in high speed hoists because of the pounding that has usually resulted from the abrupt or nearly abrupt actuation of the overturning parts.

It is an object of the present invention to provide a cage or hoist of the overturning platform type with a means for inverting the said platform at a speed which increases as the cage or skip approaches the point of discharge or delivery.

Another object is to provide mechanism which will start the tilting or overturning of the platform at a comparatively low speed, said speed increasing rapidly, the action being such as to eliminate all pounding which would otherwise be injurious to the mechanism.

A further object is to provide a skip or cage in which the overturning portion is substantially balanced when subjected to a load, the stability being maintained by the use of a latching mechanism adapted to be released automatically immediately prior to the overturning action.

A further object is to provide a cage or skip the overturning portion of which is balanced so that the inertia load is reduced to the minimum and is negotiated very slowly, no part of the operating means being required to leave or jump across a gap in the structure cooperating therewith either whilst completing the normal hoist distance or travelling as the result of an overwind, thereby avoiding the tremendous hammering which is so destructive to other types of high speed hoists.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention

shown can be made without departing from the spirit of the invention.

In the accompanying drawings the preferred form of the invention has been shown.

In said drawings—

Figure 1 is a side elevation of a skip of the combination platform and hopper type, the present improvements being combined therewith.

Figure 2 is a front elevation.

Figure 3 is a vertical transverse section through a portion of one side of the tiltable platform and adjacent parts.

Figure 4 is a section on line 4—4, Figure 3.

Figure 5 is a section on line 5—5, Figure 4.

Figure 6 is an enlarged side elevation of a portion of the tiltable platform; its gudgeon being shown in section.

Referring to the figures by characters of reference 1 designates the frame of the skip or cage adapted to travel on the guide rails in a mine shaft, this frame being provided with the usual or any preferred hoist mechanism a portion of which has been indicated generally at 2. To the inner surface of each side of the frame 1 is attached a yoke 3 which is integral with a plate 4 riveted or otherwise fastened to the frame 1. This yoke has parallel sides as shown in Figure 4 and is open at the top, the sides and bottom of the yoke being formed in their inner faces with a continuous groove 6. Furthermore as shown in Figure 3 the sides of the yoke are tapered upwardly, this taper being indicated at 7. A bolt 8 extends transversely of the yoke above the bottom thereof and constitutes a retaining means as will be described hereinafter.

In the type of skip illustrated there is provided a platform structure 9 having metal side walls 10 to each of which is secured a plate 11 provided with an opening 12. This plate is held to the bottom of the platform by an angle strip 13 and secured to the platform and angle strip is a plate 14 provided with reinforcing ribs 15, this plate being also riveted or otherwise fastened to the plate 11 and being extended across the opening 12. A gudgeon 16 is formed integral with the plate 14 and extends through the opening 12, there being an annular flange 17 at the outer end of the gudgeon adapted to rest within the groove 6. These

parts are assembled by inserting the gudgeons 16 downwardly within the yokes 3 so that the flanges 17 will slide downwardly in the grooves 6 until seated on the bottom 5 of the yokes. The bolts 8 are then inserted so as to engage the tops of the gudgeons and prevent the parts from becoming separated. Secured to the plate 11 so as to extend partly around the gudgeon 16 is an arcuate rack 18 eccentrically disposed relative to the gudgeon and having its lower end below and close to the gudgeon while its upper end is above and at some distance from the gudgeon.

15 The gudgeons 16 are so located that the platform is substantially balanced thereby, the entire load on the platform being likewise balanced so that the inertia necessary to be overcome in order to tilt the platform 20 and its load is negligible. For the purpose of actuating the platform so as to tilt it there is provided an operating means including levers 19 fulcrumed on brackets 20 and extending upwardly from segmental 25 eccentric gears 21 which mesh with the respective racks 18. Mounted on the upper ends of the levers 19 are wheels 22 connected by a cross rod or shaft 23 and a latch 24 is adapted to engage this shaft so as to hold the gear 21 against movement relative to the frame 1 while the skip is in operation below the point of discharge. An operating lever 25 slidably and pivotally 30 engages the latch 24 and has a wheel 26 designed to ride within a cam track 27 so as to disengage the latch 24 from the shaft 23 when the skip approaches the point of delivery. This latch and the mechanism employed for operating it constitutes in itself 35 no part of the present invention but already forms the subject matter of Patent No. 1,363,985 issued to me on Dec. 28, 1920.

40 Fixedly mounted within the mine shaft adjacent the point where the load is to be delivered, there are provided cam tracks 28 the lower ends of which are flared so that, as the skip approaches the upper limit of its movement the wheels 22 will be free to enter between the rails of the tracks 28. During this operation the wheel 26 will enter the cam track 27 and be shifted so as to disengage the latch 24 from the shaft 23. The cam tracks 28 provide a means for imparting a gradual swinging movement to the levers 19 as the skip travels upwardly and this movement will be such as to cause the cam gears 21 to actuate the racks 18. It will be noted that the racks and gears are so shaped and proportioned that a gradually increasing leverage will be exerted upon the rack 18 and the speed of rotation of the rack will be proportionately increased. Thus the platform 9 will be given the desired tilting or overturning action without 45 being subjected to an abrupt start but will,

on the contrary, be started gradually in its tilting action, the speed of tilting increasing gradually and being so timed that the maximum tilting movement will be attained when the skip is at the proper point of delivery. 70

Obviously with a structure such as described the objectionable pounding or hammering that has thus far been present due to the abrupt contact of operating parts is entirely eliminated even though the skip 75 travels at a high speed and, therefore, the life of the mechanism is greatly prolonged.

80 Although the overturning mechanism has been illustrated in connection with a skip having a tilting platform, a hopper, and a chute extending from the hopper it is to be understood that the improvements are not restricted necessarily to a skip of this type. Where such a skip is used, however, the cam track 28 can be employed not only for operating the mechanism to tilt the platform 9 but can also be used for actuating a bell crank lever 29 employed for swinging the pivoted chute or gate 30 mounted on the outlet portion 31 extending from the bottom 85 of the hopper 32. This mechanism does not constitute any part of the present invention but has already been disclosed in Patent No. 1,304,784 issued to me on May 27, 1919.

90 What is claimed is:—

1. The combination with a movable skip frame, of a constantly balanced load supporting structure, and cooperating fixed and movable means in the path of and on the skip frame respectively for gradually overcoming the inertia of the load supporting structure and rotating it relative to the skip frame, the velocity of rotation increasing progressively as the skip frame moves toward its terminal. 100

110 2. The combination with a movable skip frame, of a constantly balanced load supporting structure, and cooperating fixed and movable means in the path of and on the skip frame respectively for gradually overcoming the inertia of the supporting structure and rotating said structure, said means maintaining a practically uniform speed of rotation of the load structure during the slowing down period of said structure while approaching its terminal. 115

120 3. The combination with a movable skip frame, of a tilttable structure, means for locking said structure normally against tilting, stationary actuating means, means movable with the frame for engaging said actuating means to tilt the structure at a gradually increasing speed during the movement of the frame, and cooperating stationary and movable means for automatically 125 unlocking the tilttable structure prior to the tilting operation.

130 4. The combination with a movable skip frame, of a tilttable structure, an arcuate rack eccentric with the axis of rotation of

the structure, a cam gear engaging the rack, and fixed means for actuating the cam gear during the movement of the frame to tilt the structure at a gradually increasing speed independently of the speed of movement of the frame.

5. The combination with a movable frame, of a tiltable member carried thereby, an arcuate rack eccentrically disposed relative to the axis of rotation of said member, an eccentric gear meshing with the rack, and cooperating fixed and movable means for actuating the gear during the movement of the frame for tilting said member at a gradually increasing speed.

6. The combination with a movable frame, of yokes secured to the sides thereof and opening upwardly, said yokes constituting bearings, a tiltable structure within the frame, gudgeons extending therefrom and mounted in the yokes, and means for detachably securing the gudgeons against withdrawal through the open upper ends of the yokes.

7. The combination with a movable skip frame, of yokes secured to the sides thereof and opening upwardly, said yokes having grooves in the inner faces of the sides and bottoms thereof, a tiltable structure, gudgeons extending therefrom and insertible downwardly into the yokes to be supported thereby, and flanges on the gudgeons for insertion into the grooves thereby to hold the gudgeons against longitudinal withdrawal from the yokes.

8. The combination with a movable skip frame, of yokes secured to the sides thereof and opening upwardly, said yokes having grooves in the inner faces of the sides and bottoms thereof, a tiltable structure, gudgeons extending therefrom and insertible downwardly into the yokes to be supported thereby, and flanges on the gudgeons for insertion into

the grooves thereby to hold the gudgeons against longitudinal withdrawal from the yokes, and means extending transversely of the yokes and above the gudgeons for holding said gudgeons against upward withdrawal from the yokes.

9. The combination with a movable skip frame and a constantly balanced load supporting structure carried thereby, of motion transmitting means upon and movable relative to the frame, fixed means for engagement by said movable means to actuate the same through a gradually increasing area during the movement of the frame toward its terminal, and means on the load supporting structure and cooperating with the motion transmitting means for maintaining the velocity of rotation of said load supporting means practically uniform during the slowing down period of said structure while approaching its terminal.

10. The combination with a movable skip frame and a constantly balanced load supporting structure carried thereby, of motion transmitting means movably mounted on the frame, fixed means for engagement by said movable means for gradually increasing the shift thereof during the movement of the frame toward its terminal, and means on the load supporting structure and cooperation with the motion transmitting means for maintaining the velocity of said load supporting means practically uniform during the slowing down period of said structure while approaching its terminal.

In testimony that I claim the foregoing as my own, I have hereto affixed my signature in the presence of two witnesses.

DANIEL F. LEPLEY.
